FEED-TIP FOR LUBRICATORS.

1,161,296.

Specification of Letters Patent. Patented Nov. 23, 1915.

Application filed March 20, 1915. Serial No. 15,906.

To all whom it may concern:

Be it known that I, FRANK W. EDWARDS, a citizen of the United States, residing at Chicago, in the county of Cook and State 5 of Illinois, have invented a certain new and useful Improvement in Feed-Tips for Lubricators, of which the following is a full, clear, and exact description.

The feed tips of sight feed lubricators 10 usually are frustums of cones, having the discharge duct or bore extending entirely through longitudinally and open at both ends. As the oil emerges from the point it tends to flow over downward on the tip and 15 grow in volume in the surrounding water until its buoyancy and volume cause it to separate from the tip and float off through the sight feed pocket to its destination. The feed of the oil in drops is essential as a means 20 to visually inform the engineer that the lubricator is working properly. When the oil escapes from the feed tip as a film, it may eventually reach its destination, but only at a useless consumption of oil and 25 without the engineer being able to see the feed.

The use of superheated steam has made necessary the resort to a heavier oil, because the temperature of such steam equals or exceeds 30 the flashing point of ordinary light lubricating oil. This heavier oil forms in drops rather more slowly than the lighter oil, and yet the need of constant and very 35 free lubrication when superheated steam is used is quite as great and essential as when the lighter oil is used.

This invention is designed more especially to provide a feed tip for use with the heavier oils, and so constructed as to facilitate 40 the formation and release of drops of oil smaller in volume and in increased frequency.

The invention consists of a feed tip made 45 partly cylindrical and ending in a sharp attenuated conical or tapering point, and having a main longitudinal duct terminating in a transverse duct arranged at or about the base of the point, the point itself being solid or imperforate, so that the laterally 50 escaping oil instead of slipping downward, as in the case of the common conical feed tip, will tend to creep up the inclined surface of the point to its terminal, and there being there a minimum of adhering surface

the drop or globule will form quickly and 55 be as quickly detached or floated off, as I will proceed now to explain and finally claim.

In the accompanying drawings illustrating 60 the invention, in the several figures of which like parts are similarly designated, Figure 1 is an elevation and partial section of parts of a well-known sight feed condensation displacement lubricator equipped with the feed tip of the present invention. 65 Fig. 2 is a longitudinal section, on a larger scale, of another form of sight feed pocket, of approved construction, containing the feed tip of the present invention. Figs. 3, 4 and 5 are elevations of as many different 70 forms of feed tips embodying the present invention. Fig. 6 is a longitudinal section of a sight feed pocket like that shown in Fig. 2, but equipped with the prior art conical feed tip for purposes of comparison, 75 as will appear hereinafter.

1 may represent the oil bowl; 2 the condenser; 3 the boiler connection; 4 a circulating pipe; 5 the upper feed arm; 6 the lower feed arm, and 7 a sight feed pocket 80 provided with a bull's-eye or other observation glass 8, all of which and the other shown parts, excepting the feed tip itself, being of any usual or approved construction.

85 The feed tip as here shown may comprise a head 9 having the wrench-engaging lugs 10 and the externally screw-threaded portion 11 by which the feed tip may be secured fluid-tight in the sight feed pocket. 90 Above the screwthreaded portion 11 is a slender cylindrical portion 12 provided with a longitudinal duct 13 which extends through from the head 9 to a predetermined height within the cylindrical portion, but not clear through the entire length 95 of the feed tip; and in order to afford an exit for the duct, I prefer to use a transverse duct 14 arranged at the upper end of the duct 13. This transverse duct 14 may be 100 of any approved construction, and supplied with any number of branches, but the preferred construction is a single horizontal bore extending clear across and always open for the escape of the oil. The point 15 of 105 the tip is elongated so as to extend somewhat above the axial center of the observation glass 8, and this end of the tip is tapered or

beveled to a fine or practically needle point, of conical or bullet-nose or other suitable form, so as to constitute a sharp, attenuated point for collecting the oil in drops and 5 quickly letting it go into the water of condensation with which the sight feed pocket is filled and by which the drops of oil are floated off to destination.

The feed tip shown in Fig. 3 is in all essential respects the same as that shown in Figs. 1 and 2, excepting that its profile is of curved lines, or bullet-nosed, instead of straight lines as in the other views. The feed tip shown in Fig. 4 differs from that 10 15 20 shown in Fig. 3 in that the tapering point is extended somewhat below the transverse duct; and the feed tip shown in Fig. 5 differs in no other respects from that shown in Figs. 1, 2 and 3 than that it is of very much smaller dimensions.

If the prior art feed tip shown in Fig. 6 be compared with the newly-invented feed tips shown in Figs. 2, 3, 4 and 5, it will be seen that the whole of that portion of the feed tip which is exposed within the feed tip pocket is conical, or in other words, has an inclined or tapered periphery extending from the discharge end of the longitudinal duct or bore to the screwthreaded portion 25 30 35 of the base, as indicated at 16, and that the discharge end 17 of the longitudinal duct or bore is located considerably below the axial center of the observation glass, whereas the tip of the present invention has a portion of that part which is exposed within the feed tip pocket cylindrical, as at 12, and its point, which is drawn out into an attenuated needle point, extends above the axial center of the observation glass, and 40 45 50 55 that the oil instead of floating off first downward and then buoyed upward into a globule, tends to creep up the point of the tip, which is solid or imperforate and affords a very slight hold for the globule or drop as it is formed, and thus provides for its easy and quick separation from the tip. The drops form more rapidly on the attenuated fine point than on the truncated prior art point, and more frequently, and are 60 smaller than on the truncated conical point of the prior art. Tests so far made indicate that the smaller the feed tip the more rapid is the formation of the drops and the greater their frequency.

55 Referring to Fig. 4, it is to be said that tests show that a tip constructed with a tapered point extended below the transverse discharge duct, will also, as is the case with the other forms of the invention, give a reduction in the size of the oil drops and decrease in the tendency of the oil to creep down over the outer surface of the feed tip. In all of these new forms of feed tips, as 60 65 already sufficiently indicated, the drops of oil are smaller than those formed by the tips

of the prior art, and in their formation they do not creep down on the outer surface of the tip; and, furthermore, the formation of the drops is very regular in time and volume. Without thereby intending to state definitively the theory of operation, it is observed that the smaller drop, the decrease in the tendency of the oil to float down on the outer surface of the feed tip, the regularity in the formation and in the volume of the drops, and the regularity in the release of the formed drops from the tip, are due largely, if not wholly, to the fact that the oil is attracted from its point of exit from the transverse duct to the sharp needle point of the feed tip, where it speedily coalesces into successive drops and these, for lack of holding surface, let go promptly upon formation. Furthermore, tests show that in using tips constructed in accordance with the present invention, there is no tendency for the oil to float off from them in films into contact with parts of the feed pocket, but that always and under all circumstances the drops form promptly and regularly in volume and frequency, and consequently the lubrication takes place with increased uniformity and efficiency as compared with the tips of the prior art. 70 75 80 85 90

I am aware that some attempts have previously been made to decrease the size and increase the frequency of the drops, by adding to the prior art tips a wire or needle point up which the oil will ascend, but these wires were prone to bend or become defective, especially in the jarring to which they are exposed on locomotives, and instead of the drops letting go in the center of the field of vision, they would let go at any point where the wire or needle happened to be, 95 100 105 and thus not always be visible to the engineer. Tests have shown that the integral needle pointed tip of the present invention has an increased efficiency of about twenty per cent. over the wire or needle auxiliary, 110 and more than that, its point and its location relatively to the observation glass are not subject to change by movement of the locomotive, no matter how rough that movement may be. 115

What I claim is:—

1. A feed tip for lubricator sight feeds, having a discharge end of cylindrical contour provided with a longitudinal duct and an elongated and attenuated solid point tapering from a point next to the end of said duct to the terminus of said point, and also provided with a transverse duct intersecting the longitudinal duct at its end adjacent to the tapering point. 120 125

2. A feed tip for lubricator sight feeds, having a discharge end of cylindrical contour provided with a longitudinal duct terminating in a transverse intersecting duct which is arranged wholly in the sight feed 130

- pocket and is always open, and an integral imperforate needle-like point extending beyond the transverse duct and serving to quickly collect and discharge the oil globules.
5. A feed tip for lubricator sight feeds, having a discharge end of cylindrical contour provided with a longitudinal duct and an intersecting transverse discharge duct, the said tip throughout the remainder of its 10 height being solid and tapering continuously from said transverse duct to a fine terminal drop-forming and releasing point.
4. A feed tip for lubricator sight feeds, having a discharge end of cylindrical contour terminating in an elongated attenuated and imperforate needle point, the said tip having a longitudinal bore terminating short of the needle point and a transverse outlet or discharge bore intersecting the longitudi-
- dinal bore at its end and arranged at the 20 base of the needle point.
5. A feed tip for lubricator sight feeds, having a cylindrical discharge portion provided with an elongated attenuated and imperforate needle point and a longitudinal 25 duct ending short of the point and intersected by a transverse exit at the base of the needle point, whereby the discharged oil tends to creep to the point of the tip and rapidly and regularly coalesce in drops 30 which break off frequently and with regularity.

In testimony whereof I have hereunto set my hand this 18th day of March A. D. 1915.

FRANK W. EDWARDS.
